UNITED STATES PATENT OFFICE.

BENTLEY A. PLIMPTON, OF VICTOR, NEW YORK.

STRAIN-INSULATOR.

1,246,461.

Specification of Letters Patent. Patented Nov. 13, 1917.

Application filed June 28, 1917. Serial No. 177,476.

To all whom it may concern:

Be it known that I, BENTLEY A. PLIMPTON, of Victor, in the county of Ontario and State of New York, have invented certain new and useful Improvements in Strain-Insulators; and I do hereby declare the following to be a full, clear, and exact description of the same, reference being had to the accompanying drawings, forming a part of this specification, and to the reference-numerals marked thereon.

My invention has for its purpose to improve the structure of strain insulators such as are employed in connection with conductors of high tension electric currents. In a more specific aspect, the object of the improvement is to provide a cementless connection between an insulator section and a metal cap by means of a mechanical joint which does away with the necessity of a cementitious binder between the parts, while at the same time the construction is an economical one from the standpoints of both the cost of material required and the time in assembling. To these and other ends the invention consists in certain improvements and combinations of parts all as will be hereinafter more fully described, the novel features being pointed out in the claims at the end of the specification.

In the drawings:

Figure 1 is a side elevation of an insulator constructed in accordance with my invention and showing the parts in final assembled relation;

Fig. 2 is a similar view illustrating the position which the parts assume during assembling;

Fig. 3 is a vertical sectional view on the line 3—3 of Fig. 1;

Fig. 4 is a horizontal sectional view on the line 4—4 of Fig. 3;

Fig. 5 is a side elevation showing the relative position of the coöperating locking rings at the initial engaging position;

Fig. 6 is a similar view showing the relative position of the rings after they have been moved relatively and just before assuming the final locked position;

Fig. 7 is a side view of the locking member on the insulator section, and

Fig. 8 is a detail view of the tool employed in spreading the ends of the member to the position shown in Fig. 2.

Similar reference numerals in the several figures indicate the same parts.

The present structure is in the nature of an improvement on the invention disclosed in my application filed January 25, 1917, Serial No. 144,347, although susceptible of use in other relations, wherever there is a requirement for connecting a metal cap or the like with an insulator section by a locking means that holds the parts together in rigid relation, as far as relative longitudinal movement is concerned, at the same time without requiring any cementing of the porcelain to the metal.

Referring briefly to my copending application already mentioned, the structure therein comprises a split locking ring that is carried by a metal cap, and is brought into locking relation with a flange upon the insulator section by spreading the ends of the locking ring and threading the same upon the flange, which extends only partially around the body of the insulator section. In the former construction, the flange upon the insulator section was formed integral with the porcelain or other non-conducting insulating material composing the insulator section, and my present purpose is to form the locking flange separately from the insulator section making it preferably of metal, thus obtaining greater strength and resisting qualities in the insulator section without materially increasing the cost of manufacture or the difficulty of assembling.

In the present structure, 1 designates the insulator section which may be of the usual petticoat type, while 2 is a metal cap which is attached to the insulator section. The insulator section is provided with a reduced portion or neck 3 affording a shoulder 4. The reduced portion 3 receives a locking member which is in the form of a split ring 5 having an inclined surface 6 that rests against the shoulder 4 when in normal position, as shown in Fig. 3. The split ring 5 is also provided with a locking shoulder 7 that engages the locking device upon the cap, as will appear presently. The split ring 5 is provided with openings 8 and 9 to receive lugs or projections 10 upon a tool 11, whereby the ends of the locking ring, 105 and of shoulder 7, may be spread from the normal position of Figs. 1 and 3 to that shown in Figs. 2 and 5, to permit the coöperating locking device to be threaded thereon.

The cap 2 is provided at its lower end with 110 a flange 12 upon which rests a locking device in the form of a split ring 13 having at

one end a lug 14 which engages an opening in the cap, as shown in Figs. 1 to 4. The ring 13 can be inserted within the cap 2 by sufficiently compressing it so that the lug 14 engages its opening, so that when the cap is turned upon the insulator section, the locking ring 13 is also turned. In assembling the parts, the cap is placed over the insulator section with the locking ring 13 positioned thereon. Having first spread the ends of the shoulder 7 of the locking member 5, upon moving the cap downwardly upon the insulator section and then turning it to the right, the parts initially take the position shown in Fig. 5, where the ring 13 has just entered under the shoulder 7. Additional relative turning of the insulator section and cap carries the locking ring 13 farther under the shoulder 7 until it reaches the position shown in Fig. 6 where the ring 13 is almost entirely engaged with the shoulder. A very slight further turning movement, after the parts are positioned, as in Fig. 6, brings the two locking 25 rings into coincident position, with the ring 13 underneath the flange 7, as shown in Figs. 1 and 3. Upon releasing the ends of the locking ring 5, the spring action of the latter returns them to the normal position 30 illustrated in Figs. 1, 3 and 7. The flange 7 is substantially continuous and affords practically a continuous engaging surface for holding the locking ring 13, which cannot be removed without considerable difficulty, after it is once locked in place.

I claim as my invention:

1. The combination with an insulator section having a separable locking member thereon embodying a locking shoulder, of a cap coöperating with the insulator section and carrying a locking device that is brought into engagement with said shoulder by being threaded on the insulator section.
2. The combination with an insulator section having a metallic locking member thereon embodying a locking shoulder, of a cap coöperating with the insulator section and carrying a locking device that is brought into engagement with said shoulder by being threaded on the insulator section.
3. The combination with an insulator section having a separable split locking mem-

ber thereon embodying a locking shoulder, the ends of which can be spread to form a thread, of a cap coöperating with the insulator section and carrying a locking device that is brought into engagement with said shoulder by being threaded on the insulator section.

4. The combination with an insulator section having a reduced portion, of a split locking member seated in the reduced portion and embodying a locking shoulder, the ends of which can be spread to form a thread, of a cap coöperating with the insulator section and carrying a locking device that is brought into engagement with said shoulder by being threaded on the insulator section.

5. The combination with an insulator section having a separable split locking member thereon including a shoulder which is substantially continuous when in normal locking position, the ends of which shoulder can be spread to form a thread, of a cap coöperating with the insulator section and carrying a locking device in the form of a split ring that is brought into engagement with said shoulder by threading it thereon when the ends are spread.

6. The combination with an insulator section having a reduced portion affording a shoulder, of a split locking member arranged in said reduced portion normally resting against said shoulder and itself provided with a substantially continuous shoulder, the ends of which can be spread to form a thread, of a cap coöperating with the insulator section and carrying a locking device in the form of a split ring that is brought into engagement with said continuous shoulder by threading it thereon when the ends are spread.

7. The combination with an insulator section, of a cap, and locking means for holding the cap on said insulator section comprising coöperating split rings, one carried by the insulator section and the other by the cap, the ends of which rings are separable by spreading to afford threads whereby the cap may be threaded on the insulator section.

BENTLEY A. PLIMPTON.
